UNITED STATES PATENT OFFICE

LEE W. ROBINSON AND HENRY JONES, OF CHICAGO, ILLINOIS, ASSIGNEES TO LUDLOW
TYPOGRAPH COMPANY, OF CHICAGO, ILLINOIS, A CORPORATION OF ILLINOIS

PRINTING ART

Application filed October 25, 1928. Serial No. 314,944.

This invention relates to improvements in the printing art, and more particularly to means and method for producing better and more perfect printing.

5 The invention is applicable to type having relatively large, bold printing characters, such as letters, numerals and designs, and presenting printing surfaces of relatively large area to give relatively large, unbroken, 10 solid color areas or effects. It is also applicable to type having fine lines, swash swings and portions remote from the shank slot such as the ends of a head-letter Gothic "H".

The invention relates more particularly to 15 type bodies cast in matrices, for example, of brass and the like, the type forming cavity of which may be produced by forcing into a matrix blank a punch or die provided with a surface conforming to the form of type to 20 be cast in the matrix.

We have found that if the surface of the mold cavity of the matrix against which the metal of the type body is cast, is slightly roughened, the type cast therein will produce 25 better printing and more free from defects.

The roughening of the surface of the matrix referred to may be accomplished in a variety of ways. For example, the same may be sand blasted, or etched, in any suitable 30 manner, or there may be deposited on said surfaces any suitable pulverized, powdered or granular material.

As an example of one way of carrying out 35 our invention, we shall describe more particularly the method of roughing the surface of the matrix cavity by etching.

In order to aid in the understanding of 40 our invention, we have shown in the accompanying drawing in Figure 1 a view in perspective of the matrix, and in Fig. 2 a view in perspective of a type or printing body cast therefrom.

As shown in the drawings, 10 indicates a 45 matrix or mold as is ordinarily used for casting type or printing bodies, such matrix usually being held in line with, or in associated relation with other matrices in a suitable holder to permit the simultaneous casting of one or more characters on a single type slug. Such matrix or mold may be made of

brass, or other suitable material, and is provided with a cavity 11 with its bottom surface provided with the character, letter, or numeral desired, and here shown as the letter "M", indicated by 12. The letter "M", as here 55 shown, is of relatively large, boldface type, the surface 12 presenting a relatively large, unbroken, solid color area. The counter and shoulder forming surfaces 11 and 11^a and the face forming surface 12 of the matrix cavity should all be roughened; and the oblique 60 walls of the cavity as indicated by 13, which form the neck or beard 13^a of the type should also be roughened. The almost vertical side walls 14 of the cavity may also be roughened. The roughening may be accomplished in a variety of ways. We have found, for example, that the surface may be etched by suitable etching fluid, for example, oxalic acid, which effects the desired roughening. We 70 have indicated this roughening on the drawings by a slight stippling. As shown in Fig. 2, 15 indicates, in general, the entire type or printing body. The etching fluid may be applied to the surface to be roughened, or the entire matrix may be submerged in the etching fluid. 75

The strength and kind of etching fluid, and method of application may be varied to suit individual requirements. We have found, for example, that one teaspoonful of commercial strength oxalic acid dissolved in three ounces of water will produce a satisfactory etching fluid; and have obtained satisfactory results by subjecting the matrix to 80 from ten to fifteen applications of such fluid with intervening periods of exposure to the air. Obviously, however, the desired etching or roughening could be produced by the use of other and stronger or weaker etching fluids 85 with fewer or more applications. 90

While we have shown and described certain embodiments of our invention, it is to be understood that it is capable of many modifications. Changes, therefore, in the construction and arrangement may be made without departing from the spirit and scope of the invention as disclosed in the appended claims, in which it is our intention to claim 100 all novelty inherent in our invention as

broadly as possible in view of the prior art.

What we claim as new, and desire to secure by Letters Patent, is:

- 5 1. A matrix for the casting of a type body to print a solid color, said matrix having a cavity with a roughened surface and presenting relatively minute depressions distributed over substantially the entire area of the surface of said cavity.
- 10 2. As a step in the manufacture of cast type bodies to print a solid color, subjecting the surface of the matrix cavity, in which the type is cast, to the action of an etching fluid to slightly roughen said surface.
- 15 3. A matrix for the casting of a type body to print a solid color, the face forming surface of said matrix being roughened and presenting relatively minute depressions distributed over substantially the entire area of said face forming surface.
- 20 4. As a step in the manufacture of cast type bodies to print solid colors, subjecting the face forming surface of the matrix cavity in which the type is cast, to the action of an etching fluid to slightly roughen said surface.
- 25 5. As a step in the manufacture of cast type bodies to print solid colors, slightly roughening the face forming surface of the matrix cavity, in which the type is cast.

In witness whereof, we have hereunto set our hands this 19th day of October, 1928.

LEE W. ROBINSON.
HENRY JONES.
